(57) **CLAIM**

The ornamental design for a pneumatic carrier with holder for writing implement, as shown and described.

DESCRIPTION

FIG. 1 is a perspective view of a Pneumatic Carrier With Holder for Writing Implement showing my new design;

FIG. 2 is a left side elevation drawn in fragment and on an enlarged scale of the holder for the writing implement member;

FIG. 3 is an end elevation thereof drawn in fragment and shown on a slightly enlarged scale, the end opposite being substantially a mirror image;

FIG. 4 is a right side elevation thereof without the interior surface of the pneumatic carrier member;

FIG. 5 is a top plan view with respect to FIG. 2;

FIG. 6 is a bottom plan view thereof;

FIG. 7 is a top plan view showing the entire design;

FIG. 8 is a left side elevation thereof showing the interior of the pneumatic carrier;

FIG. 9 is a right side elevation thereof; and,

FIG. 10 is an end elevation thereof shown on a slightly enlarged scale, the end opposite being substantially a mirror image.

The broken lines shown in the drawings are for illustrative purposes only and form no part of the claimed design.
